CHARGING BOX FOR OPEN HEARTH
FURNACE CHARGING OPERATION

John W. Forsythe, Wilkinsburg, Pa.

Application September 5, 1942, Serial No. 457,495

5 Claims. (Cl. 214—26)

This invention relates to charging mechanism for open hearth furnaces, and relates more particularly to an improved charging box which in practical operation has a detachable connection at one end of the charging box, with one end of a charging peel or arm.

In practical operation, a plurality of charging boxes are deposited on a truck movable on a narrow-gauge trackway immediately in front of the furnace door opening, so that the peel or arm may be detachably connected to one end of any one of a plurality of loaded charging boxes positioned on the truck above mentioned.

It has been found that there are certain variations and tolerances in the nature of the interfitting and cooperating parts in the open-top socket portion at one end of the box and the peel head portion which is moved downward into said socket, by which means the detachable connection is effected.

One of the difficulties encountered has been the engagement or contacting of uneven or projecting surfaces on portions of the socket, and more particularly a tie or crossbar portion of said socket which connects the lower portion of the vertical load carrying flanges of the socket, which are intended to cooperate with vertical flange portions of the peel head, in order to afford sufficient bearing surface to withstand and uniformly distribute the forces and stresses resulting from the loaded charging box, when lifted and moved by the peel or arm. It has further been found that the engagement or contacting of the uneven portion of the tie bar, with a portion of the peel head, and possibly at times the neck portion of the peel, has resulted in concentrated and intensified stresses upon the tie bar, which at times have been of such a sufficiently high magnitude as to cause deformation or fracture of the tie bar or other associated parts of the open-top socket disposed at one end of the charging box.

One of the objects of this invention is to provide an improved charging box of such a structure as to minimize, if not eliminate, the difficulties and objections of the prior art as above noted.

A further object is to provide a charging box so arranged and constructed as to be enabled to employ a minimum thickness of metal stock for the bottom and sides, the construction being such as to enable substantially uniform expansion and contraction of the bottom and sides of the charging box under the heating and cooling

conditions to which said box is subjected in practical operation.

A further object is to provide an improved charging box of lighter weight, but yet being of such structure as to afford a maximum strength in resisting stresses and moments resulting from lifting a relatively heavy loaded charging box from one end thereof.

Further, one of the specific objects of the invention is to provide a charging box in which the relative arrangement of the parts, constituting the open-top socket at one end of the charging box for effecting a detachable connection with the head of the peel arm, are so disposed and arranged as to present a spaced or recessed portion between a tie bar, connecting vertical flanges of the socket, and between an adjacent head portion of the peel or arm, so as to minimize, if not eliminate, the possibility of fracture or deformation of such tie bar, which might otherwise result from unduly intensified and concentrated stresses, if said tie bar otherwise were permitted to come into bearing load carrying engagement with the head portion of the peel.

Generally stated, the above difficulties are minimized, if not overcome, and the above objects are obtained by providing a charging box having suitably disposed corrugations in either one or both the bottom and the sides, and an end to remedy the deformation, cracks or fractures due to the heat effect and cooling; and the difficulties at the open-top socket portion at one end of the box, involving the deformation, fracture or breaking of the crossbar due to uneven contacting surfaces and the resulting intensified stresses, are overcome by so disposing and arranging the adjacent parts of the peel head which is inserted in the socket opening, and the crossbar in its relation to the peel head and the neck portion leading thereto, as to form a recess or spaced portion between the crossbar and said adjacent parts above noted.

One selected embodiment is shown in the accompanying drawings for purposes of illustration, it being understood that various changes and other specific forms may be employed in which the spirit of the invention may be embodied, such changes and modifications being within the knowledge of those skilled in the art.

In the drawings,

Figure 1 is a top plan view of a charging box embodying the invention;

Figure 2 is a longitudinal section looking in the direction of the arrows and taken on the line II—II of Figure 1 and more clearly shows the

space or recess formed between the inner face of the crossbar at the lower portion of the open-top socket at one end of the box, and the load carrying vertical flanges of the peel head, a phantom fragment of the peel neck and head being indicated in dotted line position within the socket in Figure 2;

Figure 3 is an end elevation of the charging box looking toward the left in Figure 1; the relative position of the peel head positioned within the open-top socket is indicated in phantom by dotted line position in Figure 3; and,

Figure 4 is a vertical transverse section looking in the direction of the arrows and taken on the line IV-IV of Figure 2.

In the drawings, the charging box is indicated generally by the reference character 1 and is shown as comprising a bottom 2 and sides 3, 3a, an outer end 4, and an end 5 adjacent the open-top socket aperture 6 at one end of the box which might be referred to as the lifting end which is engaged by peel head portion 17, indicated in phantom dotted lines in Figures 2 and 3. A neck portion of the peel arm is also shown in phantom dotted lines in Figures 2 and 3 and is indicated generally by reference character 18.

The socket portion is formed by socket ends 7, 8 extending downwardly from the open-top socket aperture 6, said socket ends 7, 8 extending downwardly and forming vertical guides for the side edges of the peel head 17 as it is lowered downwardly within the socket to a position indicated in phantom dotted lines in Figures 2 and 3 as above indicated. At the outer end of the socket ends 7, 8, and disposed inwardly toward the central longitudinal axis of the charging box, are vertically extending load carrying flanges 9, 10, said vertical flanges being in substantial alignment and disposed in load carrying relation with vertical flanges 17a, said vertical flanges 17a being disposed on the peel head 17 on opposite sides of the peel neck 18 (the peel neck being shown in phantom dotted lines in Figures 2 and 3) so that said vertical flanges 17a of the peel head are in bearing contact with the inner faces 15, 16 of the vertical flanges 9, 10, respectively, forming a portion of the lifting socket on the outer side of the end 5 at one end of the charging box.

In the illustrative form as shown in the drawings, the inner bearing faces 15, 16 of the vertical flanges 9, 10, forming a portion of the socket, are shown as having a slight taper or angular disposition to a vertical plane as more clearly shown in Figure 2. Of course, the bearing face portion of the vertical flanges 17a of the peel head 17 are also correspondingly tapered or angularly disposed to have bearing contact with the inner bearing faces 15, 16 of said vertical flanges 9, 10, respectively, of the socket. It is understood, of course, that the present invention is not limited to such particular taper or angular disposition of such bearing faces, but, if desired, such bearing faces may assume a vertical plane. From the standpoint of the operation of lowering the peel head into load carrying position within the socket, a disposition of the bearing faces in a substantially vertical plane may have some advantages, inasmuch as the peel head may be lowered directly into a vertical plane to bring the peel head into functioning load carrying position within the socket. It may be preferable, if so desired, to provide the face portion of the vertical flanges 17a of the peel head, which lie adjacent to the correspondingly disposed inner ver-

tical flange faces 15 and 16, with a slight taper outwardly so that the main load bearing portion of the peel head vertical flange 17a would have contact with the vertical flange faces 15, 16 at or adjacent to their point of juncture or connection with the outer end of the ends 7, 8 which form a portion of the socket.

Such a feature may be desirable as minimizing intensified turning moments or stresses upon the unsupported portion of the vertical flanges 9, 10 adjacent the sides of the neck portion 18 of the peel or arm. Such unsupported or unreinforced faces, identified as 9a and 10a of the vertical flanges 9, 10, respectively (see Figures 1 and 3), form what might be called a recessed or slotted aperture of sufficient width to receive the peel neck 18 as the peel head 17 is lowered into load carrying position within the socket. It is preferable also that such outer vertical edge faces 9a, 10a of the vertical flange portions 9, 10, respectively, of the socket have a slight outward taper with the vertical plane as they extend upwardly, so as to provide a slotted portion which is wider at the top than at the bottom portion, in order to facilitate free entry of the peel neck 18 as the peel head is lowered into its functioning position within the socket.

A tie or crossbar 11 extends between and connects the lower end of the vertical flanges 9, 10 of the socket. Such a tie bar serves to strengthen and reinforce the lower portion of the vertical flanges 9, 10 of the socket, and the upper edge of the tie bar 11 serves to limit the downward movement of the peel neck 18 when the peel head 17 is lowered into load carrying position within the socket designated generally by reference character 6. In order to prevent contact between the inner face 12 of the tie bar 11, with the peel head 17 when lowered into functioning position within the socket, due to any unevenness of the surfaces, a spaced or recessed portion 13 is provided between the inner face 12 of the tie bar 11 and the portion of the peel head 17 adjacent thereto. The spaced or recessed portion 13 is more clearly shown in Figure 2, and also in Figure 1, in both of which figures the thickness of the tie bar 11 is shown as being less than the thickness of the lower portion of the vertical flanges 9, 10 at the point of connection of the tie bar 11 therewith.

As hereinbefore pointed out, one of the difficulties encountered in the prior art with loaded charging boxes of the type shown herein, in which the loaded charging box is lifted and transported by a peel head having a connection with the socket at one end of the charging box, has been the frequent deformation, rupture or fracture of the tie bar due to the contacting of uneven surfaces between the tie bar and the peel head, which resulted in excessive and highly concentrated stresses on the tie bar at the points of contact, which were not points primarily intended to serve as reactive points to carry the load, or to resist the intensified stresses and moments of force due to the weight of the charging box and its load, acting through the center of gravity thereof, and through a relatively long moment arm, acting about a pivotal point located at some point approximately located at one end of the loaded charging box, where the peel head is positioned within the socket. When the peel head 17 is snugly positioned within the open-top socket 6, the peel head will assume approximately the phantom position indicated in dotted lines as shown in Figure 2. As shown, the end

of the peel head is formed with oppositely tapering surfaces 23, 24 (see Figure 2) tapering in a direction so that the thickest portion of the peel head is disposed substantially centrally thereof, the thinner portion of the peel head being adjacent the top and bottom portion of the socket, when the peel head is positioned in said socket. Such an arrangement of tapering surfaces on the peel head permits of two positions of the peel head, displaced by 180°, which may be utilized for lowering the peel head into the socket 6.

As shown, the lower portion of the socket is formed by an angularly disposed wall 21 which is disposed adjacent to and may be in substantial parallelism with, and in bearing contact with, the lower tapering face 24 of the peel head. Any bearing contact between the wall 21 of the socket and the tapering face 24 of the peel head would serve as a reacting point or area tending to resist any turning moment or forces about any pivotal point of support in the peel head 17, or the neck portion 18 of the peel or arm. The angularly disposed wall 21 extends upwardly from the bottom of the socket, to a point substantially between the top and the bottom of the socket, such, for example, as a point indicated by reference character 22 where the upper end of the wall 21 merges with the end wall 5 of the charging box.

With further reference to the tie or crossbar 11, as shown in Figure 1, the outer face 14 of said crossbar, connecting the lower portions of the vertical flanges 9, 10, is shown as being in the same plane as the outer faces 19 and 20 of said vertical flanges 9 and 10, respectively. However, this is not an essential feature, the important feature being that the cross or tie bar 11 be thinner than the thickness of the vertical flanges, and of such a dimension as to assure the provision of a space portion or recess 13 between the inner face 12 of the tie bar and the adjacent portion of the peel head when positioned in the socket.

As a means of providing a body portion for the charging box of minimum thickness of metal, which will provide a structure of maximum strength and minimize the deformations, fractures and surface cracks, due to the expansion and contractive forces when the charging box is subjected to intense heating, followed by cooling, there is provided a feature which enables maximum strength to be had and also permits expansion and contraction of the various parts of the charging box, without encountering excessive and concentrated stresses that are likely to result in surface cracks or deeper fractures.

As shown in the drawings, the bottom 2 of the box is formed by a succession or series of corrugations including the convex or crest portions 25 and followed by the concave or furrow portion 26 so as to form a wave-like appearance on the outer surface of the bottom 2. The inner side of the bottom is preferably similarly formed by corrugations including a succession of convex portions 27, followed by concave portions 28, the convex portion 27 on the inner side of the bottom underlying and conforming to the concave portion 26 on the outer face of the bottom, and likewise the concave portion 28 on the inner face of the bottom, underlying and conforming to the convex portion 25 on the outer face of the bottom. Preferably, the extent or depth of the corrugations as indicated by the depth between the concave portions 26, 28 and the convex portions 25, 27 respectively, is greater than the thickness

of the metal comprising the bottom 2. Such a series of wave-like corrugations permit a considerable degree of expansion under intense heat and subsequent contraction upon cooling, without imposing undue stresses which are likely to result in fractures of the metal, and also minimizes the likelihood of formation of surface cracks. As shown, the crest or convex portions of the corrugations extend transversely of the 5 charging box across the bottom thereof, but it is understood, that if desired, other dispositions and arrangements of the corrugations may be had, such for example as by disposing the crest and furrow portions in longitudinal relation to 10 the length of the charging box. The corrugations afford a stiffening or reinforcing strengthening effect in the direction in which the corrugation extends, or more specifically, in the direction in which the convex or crest portion of 15 20 the wave-like corrugation extends.

As shown in the drawings, the sides 3 and 3a of the charging box are also provided with corrugations having a series of convex or crest portions 29, followed by a concave or furrow portion 25 30 on the outer face of the sides (see particularly Figures 1 and 4). On the inner face of the sides there is also presented a series of convex or crest portions 31, corresponding in position with the concave portion 30 on the outer face of the side, 30 and also a concave or furrow portion 32 on the inner face of the side, which concave portion 32 corresponds in general form to the convex crest portion 29 on the outer face of the charging box side.

35 As shown in the drawings, the corrugations in the bottom are continuous with the corrugations in the two sides 3, 3a, but it is understood that this is not necessary as the corrugations may be arranged in various forms in the bottom only, or the sides only, or in both the bottom and the sides, and in various relations best adapted to meet the particular requirements of strength and weight desired, and the requirements of expansion and contraction under the temperatures involved.

40 As shown, corrugations are formed in the end wall 4 of the charging box. The corrugations are shown as being of the same general form as the corrugations in the bottom and sides, said corrugations 33 being shown as extending in a vertical plane, extending from the top to the bottom of the end 4. Here also, the size, arrangement and relation of the corrugations in the end 4 may be varied as desired and may extend in a 55 horizontal plane and may be of a different size than those employed in the bottom or side, dependent upon the conditions met with in practice.

50 Preferably, stiffening ribs 34 or a series of such ribs may be provided as reinforcing members, extending upward from the bottom of the box and along the inner face of the end 4. Such strengthening and reinforcing ribs 34 minimize the likelihood of the end 4 being displaced or 55 forced outwardly longitudinally of the charging box.

60 If desired, apertures 35 may be provided in the bottom 2 of the charging box, such aperture being provided in suitable number and various arrangements as desired. Such apertures 35 serve as 70 ventilating apertures, and also serve as drainage apertures in the event of the presence of liquid within the box. Preferably, the flange 36 is formed about the upper edge of the sides 3, 3a and end 4 of the charging box.

Referring more particularly to Figures 1 and 3, there are shown strengthening strut portions 37, 38, extending from the vertical flange portions 10 and 9, respectively, in a somewhat diagonal direction to the sides 3a and 3, respectively. Such strut portions extend substantially vertically from the bottom to the top of the charging box and serve to reinforce the vertical flanges 9, 10 of the socket.

Referring more particularly to Figure 3, there is shown an aperture 40 in the strut portions 37, 38, said aperture 40 being substantially between the top and the bottom of the box. The aperture 40 is shown in substantial alignment with a cut-away or slotted portion 39 (see Figure 3), said slotted portion 39 being formed intermediate the ends of the vertical flanges 9, 10 of the socket. Such a structure permits the passage of a locking bar to pass therethrough as one means of locking the socket end of the charging box in lifting relation with the neck and head portion of the peel or arm. Of course, a suitable passage or opening also would be provided in the neck and head portion of the peel to receive such a locking bar. Such an aperture in the peel or arm portions is not shown herein as it constitutes no part of the present invention.

In certain types of manipulating mechanism for the charging box, a locking bar is moved longitudinally of the box in order to effect a locking relation between the head portion of the peel arm and the charging box. In order to provide for such a longitudinal movable locking bar, suitable apertures 41 may be provided in the ends 4 and 5 of the charging box.

While one preferred form of the invention has been shown and described herein, it is understood that various changes and modifications may be made by those familiar with the art without departing from the spirit and scope of the invention as defined in the appended claims.

I claim:

1. In a charging box for charging open hearth furnaces adapted to be lifted by a detachable connection between the head portion of a peel or arm, and an open-top socket portion disposed at one end of the box, strengthening means to facilitate lifting the loaded charging box, said strengthening means including corrugations in the sides and bottom of said charging box extending transversely and as continuous wave-like folds, and being formed by deforming substantially uniformly the entire thickness of metal, the depth of the concave or valley recess portion of the corrugation being greater than the thickness of the metal stock from which the charging box is made, said open-top socket including spaced end portions extending outwardly from the end and in a direction longitudinally of the charging box, and extending substantially from the top to the bottom of the box, spaced vertical flange portions at the outer end of said spaced end portions, the space between said vertical flanges forming an open slot-like aperture adapted to receive the neck portion of the peel, the inner face of each of said vertical flange portions presenting a load carrying bearing portion, extending from substantially the bottom to the top of the charging box, and adapted and disposed to lie in alignment with, and cooperate with, the vertically disposed load carrying flanges of the peel head disposed on opposite sides of the neck portion, to carry the weight of the loaded charging box when the peel head portion is positioned within the socket, and a tie bar, con-

necting the lower end of said spaced vertical flange portions of the socket, said tie bar being spaced from the head portion, and other parts of the peel, at the inner face of the tie bar, when said peel head is in load bearing position in said socket, and presenting a recess or spaced portion between the tie bar and the peel, whereby the likelihood of deformation or fracture of the tie bar, or other parts of the socket, through concentrated stresses resulting from accidental or limited bearing contact with the load carrying peel head or neck, is minimized, if not eliminated.

2. In a charging box for charging open hearth furnaces, adapted to be lifted by a detachable connection between the head portion of a peel neck or arm, and an open-top socket portion disposed at said end of the box, and strengthening means for the socket at one end of the box, outside of said end wall of the box, to minimize or eliminate the likelihood of fracture due to the concentration of stresses between certain interfering or contacting uneven surfaces between portions of the peel head, and portions of the socket, said strengthening means comprising an open-top socket having spaced end portions extending outwardly from the end and in a direction longitudinally of the charging box, and extending substantially from the top to the bottom of the box, spaced vertical flange portions, at the outer end of said spaced end portions, disposed substantially normal to said end portions, the space between said vertical flanges forming an open slot-like aperture adapted to receive the neck portion of the peel, the inner face of each of said vertical flange portions presenting a load carrying bearing portion, extending from substantially the bottom to the top of the charging box, and adapted and disposed to lie in alignment with, and cooperate with, the vertically disposed load carrying flanges of the peel head disposed on opposite sides of the neck portion to carry the weight of the loaded charging box when the peel head portion is positioned within the socket, and a tie bar, connecting the lower end of said spaced vertical flange portions of the socket, when said peel head is in load bearing position in said socket, and presenting a recess or spaced portion between the tie bar and the peel, whereby the likelihood of deformation or fracture of the tie bar, or other parts of the socket through concentrated stresses resulting from accidental or limited bearing contact with the load carrying peel head or neck, is minimized, if not eliminated.

3. In a charging box for charging open hearth furnaces, adapted to be lifted by a detachable connection between the head portion of a peel or arm, and an open-top socket portion disposed at said end of the box, said peel head portion having a neck portion, strengthening means for the socket at one end of the box, to minimize or eliminate the likelihood of fracture and the concentration of stresses between portions of the peel head, and portions of the socket, said strengthening means comprising an open-top socket including spaced end portions extending outwardly from the end and in a direction longitudinally of the charging box, spaced vertical flange portions, at the outer end of said spaced end portions, disposed substantially normal to said end portions, the space between said vertical flanges forming an open slot-like aperture adapted to receive the neck portion of the peel, the inner face of each of said vertical flange portions presenting a load carrying bearing portion,

and adapted and disposed to lie in alignment with, and cooperate with, the vertically disposed load carrying flanges of the peel head disposed on opposite sides of the neck portion, to carry the weight of the loaded charging box when the peel head portion is positioned within the socket, and a tie bar connecting the lower end of said spaced vertical flange portions of the socket, said tie bar being spaced from the head portion, at the inner face of the tie bar, when said peel head is in load bearing position in said socket, and presenting a recess or spaced portion between the tie bar and the peel, whereby the likelihood of deformation or fracture of the tie bar, or other parts of the socket, through concentrated stresses resulting from accidental or limited bearing contact with the load carrying peel head or neck, is minimized, if not eliminated.

4. In the combination of a charging box and a peel head disposed at one end of a peel neck, said charging box having an open-top socket portion at one end, and including a plurality of spaced vertically disposed flanges forming an open slot-like aperture adapted to receive the head and neck portions of the peel, a tie bar connecting the lower end of said spaced vertical flanges of the socket in such a manner as to be spaced or recessed from the head portion of the peel when said head portion is disposed in load carrying position in the open-top socket portion at one end of the charging box.
5. The combination, as defined in claim 4 and including laterally disposed corrugations in the sides and bottom of said charging box.

JOHN W. FORSYTHE.
